UNITED STATES PATENT OFFICE.

EUGENE R. ALDERMAN, OF HOLYOKE, MASSACHUSETTS, ASSIGNOR TO FARR ALPACA COMPANY, OF HOLYOKE, MASSACHUSETTS, A CORPORATION OF MASSACHUSETTS.

BOBBIN-HANDLING MACHINE.

Application filed May 12, 1926. Serial No. 108,636.

This invention relates to improvements in bobbin handling machines and is directed more particularly to improvements in machines of the class described in U. S. Letters Patent 1,556,469, issued to me October 6, 1925.

By reference to the patent referred to, it will be observed that the bobbins are delivered one by one onto the receiving spindles of a rotating carrier. If the bobbins are defective by being warped, they will not slip entirely onto the said spindles and will project therefrom to act on certain mechanism so that the machine will be stopped thereby to allow the operator to remove such defective bobbins from the spindle, while such perfect bobbins as are received by the spindles will be delivered to a receptacle below which is provided therefor.

The principal object of this invention is the provision of mechanism for use in conjunction with machines similar to that referred to for ejecting warped bobbins or bobbins having undersized openings from the spindle into a receptacle, the said mechanism being adapted and arranged to operate without stopping the machine, whereby the delays caused by defective bobbins may be entirely eliminated.

Other objects and advantages of the invention and the novel features of construction thereof will be apparent from the following description which is illustrated in the form at present preferred by means of the accompanying drawings in which:

Fig. 1 is a side elevational view partly in section showing the mechanism for ejecting a warped bobbin from a spindle of a carrier;

Fig. 2 is a plan view taken on the line 2-2 of Fig. 1; and

Fig. 3 is an enlarged perspective view of the ejector actuating lever.

Referring to the drawings in detail, a carrier wheel 1 having bobbin receiving spindles 2 is rotated in a step by step manner on a shaft S by means of a Geneva 3 actuated by a Geneva crank or driver 4 fixed on a shaft 5 which is geared to and driven from a shaft 6. This mechanism is similar to that shown and described in the patent referred to and will similarly function to rotate the carrier wheel in a counter-clockwise direction. This movement will carry the bobbins received on

the spindles when in the top center position around to a point where they fall by gravity 55 therefrom and into a receptacle 7 therebelow, provided, of course, such bobbins are straight and unwarped so as to slip easily over the spindles.

The bobbins may be released one by one 60 from a spout and delivered onto the spindles in their top center position by means of the mechanism shown and described in the before-mentioned patent. If the bobbins are unwarped and straight and are provided 65 with suitable sized bores, they will slip entirely over the spindles and rest on the carrier and as the spindle is carried into downwardly inclined positions, the bobbin will 70 slip or fall therefrom into a receptacle 7.

Should a bobbin that is either warped or has an undersized bore be delivered onto the spindle, then obviously it will not properly slip over the spindle and will project beyond the end thereof as shown in dotted 75 lines at B'. This imperfect bobbin it is desired to separate from the perfect ones delivered to the receptacle 7 and to accomplish this I provide the novel mechanism forming a part of this invention and now to 80 be described.

A detector lever oscillatable on the shaft S has a bifurcated or forked upper arm 11 and a lower arm 12. A roll or pin 13 carried at the extremity of the arm 11 is arranged 85 to lie in the path of any defective bobbin that extends beyond the end of its spindle as shown, and as the roll is engaged by the end of the bobbin in its rotation, the arm will be swung downwardly thereby.

A control lever 14 pivoted at 15 is connected by a suitable rod 16 to the arm 12 of the lever just described and is swung thereby to the right when an imperfect bobbin strikes the detector lever 11. An impulse 95 lever 17 pivoted at 18 to a suitable support 10 has a cam shaped lower end 18' arranged thereon for a hinged or swinging action in a plane transversely to the swinging movement of the lever and is arranged to be 100 moved into and out of the path of a pin or roll 19 carried by a crank 20 fixed to the continuously rotating shaft 6.

A control rod 21 fixed to the upper end of control lever 14 is slidably in a guide 22 105 carried by the hinged cam end 18' of the

lever 18 and is offset substantially in a horizontal plane, as best shown in Fig. 3. This rod is preferably so arranged that it will, when it is reciprocated through the guide, move the cam end 18' into and out of the path of the roll 19 accordingly as the lever 14 is rocked in one direction or the other.

An operating lever 23 pivoted at 24 to the support 10 is also pivotally connected 10 at its upper end to the upper end of the impulse lever 17 while its lower end is likewise pivoted to an ejector member E which is 15 slidable along the arm 11 of the detector lever. The ejector E is provided at its forward end with downwardly depending guides in the form of rolls 25 which work in connection with the bifurcated arm to 20 guide the same therealong. As shown in Fig. 2, the ejector E is provided with a laterally extending lug or ledge 26 which is disposed and arranged to strike against the lower end of a bobbin on the spindle and will in its reciprocating movement along the lever arm 11 eject a bobbin from the spindle and into a chute C which is disposed so 25 as to have its delivery mouth over a receptacle 27 therebelow for receiving rejected or imperfect bobbins. Means are provided for returning the parts to the position shown 30 after each ejecting operation and may comprise springs 30 and 32, as shown, arranged to pull the levers 17 and 14 into engagement with the stops 31 and 33.

In operation, when for any of the reasons 35 before mentioned, a bobbin such as indicated at B' does not slip entirely over the spindle and projects therebeyond, it will, as it is carried by the wheel, strike the roll 13 of the arm 11 and move said arm downwardly. 40 This movement will shift the control lever 14 to the right and the rod 21 thereof will locate the cam end 18' of the lever 17 in the path of the rotating roll 19. The cam end 18' will be engaged by the roll 19 of the 45 crank 20 and will be swung quickly in a counterclockwise direction. This movement will impart a swinging movement to the ejector operating lever 23 so as to move the ejector E up along the arm 11 whereby the 50 ledge 26 of the ejector will engage the bottommost or rear side of the bobbin and eject it from the spindle into the chute C. The springs 30 and 32 will quickly return the parts to their inoperative position shown for 55 a subsequent ejecting movement.

Ordinarily properly sized or perfect bobbins are carried by the spindle until they fall therefrom into the receptacle, but in case they should not fall readily therefrom, 60 I provide a means to positively remove them from the spindle which comprises the following.

A cam member 34 adjustably mounted on a bracket 35 is disposed adjacent the rotatable carrier and has a curved outer periph-

eral face 32' preferably arranged in an eccentric relation with the axis of rotation of the carrier. As the bobbins are rotated past the cam 34, its face 34' will engage with the lower or bottom end of the bobbin and gradually cam it from the spindle during the rotation of the carrier and thereby insure that all spindles are empty when they arrive at their top center or bobbin receiving position.

From the above, it will be observed that I have provided means for ejecting imperfect bobbins from the spindles of the carrier wheels that is controlled in its operation by the imperfect bobbins during the rotation thereof, whereby it is possible to test a greater number of bobbins than formerly and the necessity of the manual removal of imperfect bobbins is eliminated.

I am aware that many changes may be 85 made in the form of the invention without departing from the scope thereof and I prefer to be limited by the appended claims rather than by the foregoing description.

What I claim is:

1. The combination of a bobbin handling machine having a movable carrier for receiving and detecting certain imperfections in bobbins with means for removing imperfect bobbins from said carrier comprising, an ejector, ejector operating mechanism, actuating means in the path of imperfect bobbins and movable thereby to connect the said ejector and operating means whereby an imperfect bobbin is ejected from the carrier.

2. The combination of a bobbin handling machine having a movable bobbin receiving spindle for testing the characteristics of bobbins for fitting tightly or loosely upon a 105 spindle with means for removing therefrom bobbins having tightly fitting bores comprising, an ejector for acting on said bobbins, operating means therefor and a detector disposed in the path of movement of tightly fitting bobbins actuated thereby to connect the said ejector with the operating means.

3. The combination of a bobbin handling machine having a movable bobbin receiving spindle for testing the characteristics of bobbins for fitting tightly or loosely upon a spindle with means for removing therefrom bobbins having tightly fitting bores comprising, an ejector for acting on said bobbins and operating means therefor normally out of interengagement, a detector in the path of movement of bobbins having tightly fitting bores and actuated thereby to bring the said ejector into operable engagement with the operating means therefor.

4. The combination of a bobbin handling machine having a plurality of intermittently movable bobbin receiving spindles for testing the characteristics of bobbins for fitting tightly or loosely upon a spindle with means

for removing therefrom bobbins having tightly fitting bores comprising, an ejector for acting on said bobbins as said spindles arrive at a predetermined point, operating 5 means therefor normally out of engagement therewith, a detector disposed in the path of movement of a bobbin fitting tightly on said spindles actuated thereby to interengage the ejector with said operating means.

10 5. The combination of a bobbin handling machine including a rotatable member having a plurality of bobbin receiving spindles for testing the characteristics of bobbins for fitting tightly or loosely on a spindle with 15 means for removing bobbins therefrom having tightly fitting bores comprising, ejector mechanism for acting on the bobbins, actuating means therefor, the said ejector mechanism having a part movable towards and 20 away from the path of movement of said actuating means, and a detector disposed in the path of movement of said tightly fitting bobbin and operated thereby for positioning the movable part of the ejector in the path 25 of the said actuating means whereby the ejector is operated to remove the said tightly fitting bobbin from said spindle.

6. The combination of a bobbin handling machine including a rotatable member having a plurality of bobbin receiving spindles for testing the characteristics of bobbins for fitting tightly or loosely on a spindle with 30 means for removing bobbins therefrom having tightly fitting bores comprising, a detector disposed in the path of movement of tightly fitting bobbins, an ejector movable on said detector and actuating means therefor, the said detector including a member movable into the path of the actuating 35 means, and means connecting said detector and said member whereby as the detector is engaged by a tightly fitting bobbin the ejector is actuated by moving said member into the path of said actuating means.

45 7. The combination of a bobbin handling machine including a rotatable member having a plurality of bobbin receiving spindles for testing the characteristics of bobbins for fitting tightly or loosely on a spindle with 50 means for removing bobbins therefrom having tightly fitting bores comprising, a detector disposed for a swinging movement on an axis parallel to that of said rotating member having a portion in the path of bobbins fitting tightly on said spindles, an ejector movable therealong and a rotating actuating member therefor, the said ejector having a cam movable into and out of the path of said actuating member and connections between 55 said detector and said cam whereby the latter is moved into the path of said actuating

member as the detector is engaged by a tightly fitting bobbin.

8. The combination of a bobbin handling machine including a rotatable member having a plurality of bobbin receiving spindles for testing the characteristics of bobbins for fitting tightly or loosely on a spindle with 65 means for removing bobbins therefrom having tightly fitting bores comprising, a detector disposed for a swinging action on an axis substantially parallel to that of said rotatable member having a portion in the path of movement of a tightly fitting bobbin, an ejector movable thereon having a portion for engaging the underside of bobbins carried by said spindles, a continuously rotating crank, means for connecting said ejector and crank including a cam thereon movable into or out of the path of said crank and connections between the detector and cam whereby the cam is moved into the path of said crank as it is engaged by a tightly fitting bobbin.

9. The combination of a bobbin handling machine having a movable bobbin receiving spindle for testing the characteristics of bobbins for fitting loosely or tightly upon a spindle so as to extend therebeyond with 80 mechanism for removing bobbins from said spindles comprising, an ejector disposed in the path of a bobbin extending beyond a spindle and actuated thereby to remove said bobbin and a member disposed adjacent said spindle arranged to engage and remove such bobbins as do not extend beyond said spindle. 85

10. The combination of a bobbin handling machine having a movable bobbin receiving spindle for testing the characteristics of bobbins for fitting loosely or tightly upon a spindle so as to extend therebeyond with 90 mechanism for removing bobbins from said spindles comprising, an ejector disposed in the path of a bobbin extending beyond a spindle and actuated thereby to remove said bobbin, and a cam member for removing 95 such bobbins as do not extend beyond said spindle disposed so as to have its face engage the lower side of a bobbin as the spindle moves therewith.

11. The combination of a bobbin handling machine having a movable receiving spindle for testing the bore of bobbins for fitting tightly upon a spindle with mechanism for removing from said receiving spindles bobbins which fit tightly thereon and extend 100 therebeyond comprising an ejector mechanism rendered operative by a detector disposed in the path of movement of said tightly fitting bobbin. 115

In testimony whereof I have affixed my 120 signature.

EUGENE R. ALDERMAN.
